UNITED STATES PATENT OFFICE.

EDWARD A. TUTTLE, OF NEW YORK, N. Y.

DESIGN FOR A HOT-AIR AND VENTILATING REGISTER.

Specification forming part of Design No. 5,471, dated January 9, 1872.

to all whom it may concern:

Be it known that I, EDWARD A. TUTTLE, of the city of New York, in the county and State of New York, have invented a new and original design for Hot-Air and Ventilating Registers, of which the following is a specification:

The nature of my invention is fully represented in the accompanying photographic illustration, to which reference is made.

In this design there are three concentric circles—*a*, *e*, and *c*, one, *a*, forming the central figure, and the second, *e*, being of about thrice the diameter of that. The rest of the design is filled up by arabesques composed mainly of

lyre-shaped figures *o* and *i*, the volute portions of the former joining the circle *e*, and those of the latter being interlocked with the circle *e*, and continued so as to form a figure 8 (*r*) in connection with the lyres *o*.

What I claim as my design for a register is—

The three concentric circles and interlocked figures *i*, *o*, and *r*, as shown and described.

EDWARD A. TUTTLE.
